UNITED STATES PATENT OFFICE.

RAGNAR O. W. LUNDIN, OF NEW BRITAIN, CONNECTICUT, ASSIGNOR TO THE TRUMBULL MANUFACTURING COMPANY, OF PLAINVILLE, CONNECTICUT, A CORPORATION OF CONNECTICUT.

ELECTRIC SWITCH.

1,224,116.

Specification of Letters Patent. Patented Apr. 24, 1917.

Application filed December 16, 1915. Serial No. 67,121.

To all whom it may concern:

Be it known that I, RAGNAR O. W. LUNDIN, a citizen of the United States of America, residing at New Britain, Connecticut, have ⁵ invented a new and useful Electric Switch, of which the following is a specification.

This invention relates particularly to wall or flush type switches and the general objects of the invention are to provide a positive, quick acting switch of simple and inexpensive construction, consisting of but few parts and of compact design. ¹⁰

A special object is to so construct the switch that a comparatively slight movement of an actuating member will be sufficient to effect the actuation of the switch. ¹⁵

In the achievement of the above and other objects I employ a swinging contact making lever and operate the same by means of a ²⁰ rocking lever which is pivoted at a point to one side of the point of pivotal support of the swinging contact making lever and which has a spring supporting portion disposed substantially in the plane of pivotal support of the contact making lever, with a switch throwing spring connected between this off-set spring supporting portion of the rocking operating lever and the free end of the contact making lever. ²⁵

The switch operating lever is preferably ³⁰ actuated by means of push buttons connected to the ends thereof, a special feature of the invention residing in the manner of securing the push button to the operating lever. ³⁵

Another feature of the invention is a form of arched support for the switch operating and contact making levers and a simple and effective method of mounting these levers on ⁴⁰ said support.

Various other features and details of construction will appear as the specification proceeds and will further be made clear by consideration of the accompanying drawing ⁴⁵ which illustrates the invention embodied in a practical and preferred form.

In this drawing:—

Figure 1, is a plan view of a wall switch having the invention incorporated therein, ⁵⁰ the cover and supporting yoke being omitted for the sake of clearness.

Fig. 2, is a detached detail view of the actuating parts of the switch and the mounting therefor.

Fig. 3, is a longitudinal sectional view of ⁵⁵

the switch taken substantially on the plane of the line 3—3 of Fig. 1.

Fig. 4, is a transverse sectional view taken substantially on the plane of the line 4—4 of Fig. 1. ⁶⁰

Fig. 5, is a view of the switch parts in separated relation.

The switch mechanism is supported on a suitable insulating base 7, which, as illustrated, may be hollow, in the form of a box, ⁶⁵ and adapted to be supported in proper position in a wall or elsewhere by means of a bridge piece or supporting yoke 8 extending across the open front side of the box and secured thereto by screws 9. ⁷⁰

The movable members of the switch comprise only two main parts, a contact making lever 10 and a switch operating lever 11 and these movable parts are preferably both supported in a single supporting bracket 12. ⁷⁵

In the form of the invention illustrated the contact making lever is in the form of a substantially U-shaped member having substantially parallel side arms 15 joined together at their lower ends and provided at ⁸⁰ their upper ends with laterally extending pintles 16.

The supporting bracket is shown arched in its intermediate portion, providing the upright sides 18 connected by the top 19, ⁸⁵ base or foot portions 20 being provided at the opposite ends of the bracket to receive screws 21 or other suitable fastenings passed up through the base.

Socket 22 for the contact making lever ⁹⁰ pintles are provided in the upstanding side portions of the arched bracket and these sockets are preferably elongated in the form of slots, the opposite end portions 23 of which provide bearings for the rocking ⁹⁵ switch operating lever. These bearing slots are preferably left open at one side as indicated at 24 to facilitate assemblage of the parts.

The rocking switch operating lever 11 is ¹⁰⁰ preferably arched upwardly intermediate its ends and provided at the crown of said arch with a spring seat 25, standing when the lever is in a central position, substantially in the plane of the contact making lever pivot. This switch operating lever is provided with pintles 26 engaging in the socket 23 in the opposite sides of the arched support and is provided further in the case ¹⁰⁵ illustrated with oppositely extending arms ¹¹⁰

27 and 28 to which operating push buttons 29 and 30 are connected.

The contact making lever is thrown with a quick snappy movement by means of a spring 31 having hooks 32 and 33 at its opposite ends engaging respectively with the spring seat 25 on the arched portion of the switch operating lever and with a spring seat 34 provided on the lower free end of the contact making lever. These spring seats as here shown may be provided by simply forming separated openings 25' and 34' in the respective members connected by a narrow bridge portion as indicated which forms the spring seat proper and these bridge portions may be struck up out of the plane of the metal of which they are a part, as indicated in the several views so that the hooks can be more readily engaged therewith. By reason of this construction the hooks on the springs, stand, when the parts are assembled, in planes parallel to the pivotal planes of the two levers. Consequently there is no liability for the springs to become unhooked or displaced and in the swinging movement of the two levers the spring hooks simply pivot easily on the bridge pieces or spring seats with which they are engaged.

The push buttons, constituting the handles or means for operating the switch illustrated, have relatively flat shanks 35 formed with openings 36 adjacent the lower ends thereof and with notches 37 in their lower edges. The oppositely extending arms of the switch operating lever are formed with openings 38 adjacent the ends thereof and with entrance slots 39 opening into said openings. It will be evident from this construction that the push buttons can be operatively engaged with the switch operating lever by simply entering the notched end portion of the shank through the slot 39 into the pivot opening 38 in the switch operating lever as indicated at the left in Fig. 5 and turning the button up into the upright position as shown at the right end of this lever in said figure. A reversal of this operation obviously will permit detachment of the operating push buttons from the switch operating lever.

In the particular embodiment illustrated the contact making lever in its active position engages between and bridges a pair of contacts 40 and in its other extreme position is out of engagement with all contacts, the throw or extent of movement of the contact making lever being limited by the inturned stops 41 provided at the lower end of the arched supporting bracket.

The operation will perhaps be best understood by reference to Fig. 3 wherein it will be seen that when the left hand push button 29 is depressed the left hand end of the switch operating lever will be rocked downwardly, the effect of which will be to carry the spring

seat 25 with which the upper end 32 of the throwing spring is engaged from the position at the right hand side of the contact making lever pivot over to a position in line with said pivot and thence on toward the left past said pivotal point, the spring acting as the spring support swings on past the said center, to snap the contact making lever toward the left with a quick movement. The spring now exerts its tension to hold the contact making lever in the position to which it has thus been shifted, said lever therefore remaining in the position in which it has been shifted until the opposite push button is operated.

The arching of the switch operating lever and the engagement of the spring with the arched portion of this lever enables a relatively slight movement of said lever to effect the operation of the switch, and it will be seen too, that this construction provides an extremely compact arrangement.

The rocking movement of the switch operating lever is limited, in the construction illustrated, by the engagement of said lever with the under side of the top 19 of the arched supporting bracket as indicated in Fig. 3 and the swinging movement of the contact making lever past the pivot of the operating lever is provided for by off-setting or looping the contact making lever as indicated at 45 around the switch operating pintles.

The open-sided bearing slots permit ready engagement of the pintles on the two levers in their bearings and it will be seen that the switch throwing spring when engaged between said levers exerts its tension to hold the pintles at opposite ends of the slots and to prevent disengagement of said pintles from said open bearings.

What I claim is:—

1. In a switch of the character described, a swinging contact making lever, a relatively stationary contact arranged to be engaged thereby, a rocking switch operating lever pivotally supported below the point of pivotal support of the contact making lever and provided with a spring seat substantially in the plane of the pivotal support of the contact making lever, a tension spring stretched between the contact making lever and the switch operating lever connected to said spring seat at one end and connected with the contact making lever at its opposite end and means for rocking said switch operating lever to thereby carry that end of the spring which is engaged with the spring seat to one side of the pivotal center of the contact making lever.

2. In a switch of the character described, a swinging contact making lever, a relatively stationary contact arranged to be engaged thereby, a rocking switch operating

- lever pivotally supported below the point of pivotal support of the contact making lever and provided with a spring supporting portion arched upwardly toward the pivotal support of the contact making lever, a spring engaged with said arched portion at one end and with the contact making lever at its opposite end, and means for 5 rocking the switch operating lever.
- 10 3. In a switch of the character described, a supporting bracket having a slot therein, said slot being open at one side intermediate the ends of the same to admit pivots for en- gagement in the opposite ends of the slot, a contact making lever having a pivotal en- 15 gagement in one end of said slot, a switch operating lever having a pivotal engagement in the opposite end of said slot and arched toward the contact making lever pivot and a throwing spring connected between the 20 contact making lever and the arched portion of the switch operating lever and exerting tension to hold the pivots of said levers at the opposite ends of said open pivot slot.

RAGNAR O. W. LUNDIN.
